Primary Examiner — Jonathan J Han

(57) **CLAIM**

The ornamental design for a shoe as shown and described.

DESCRIPTION

1. Shoe

1.1 : Left

1.2 : Right

1.3 : Front

1.4 : Back

1.5 : Top

The design shows a sports shoe with a springy synthetic sole and a knitted upper with various knitted patterns and synthetic reinforcements in the toe area and along the eyelet strips; in figure 1.5, the middle section does not form part of the protected design and the area has been dotted.

1 Claim, 5 Drawing Sheets
